UNITED STATES PATENT OFFICE.

HERBERT A. MOODY, OF HUDSON FALLS, NEW YORK.

MACHINE FOR MAKING PULP-BOARD.

1,002,425.

Specification of Letters Patent.

Patented Sept. 5, 1911.

Application filed October 29, 1910. Serial No. 589,826.

To all whom it may concern:

Be it known that I, HERBERT A. MOODY, a citizen of the United States, residing at Hudson Falls, in the county of Washington and State of New York, have invented certain new and useful Improvements in Machines for Making Pulp-Board, of which the following is a specification.

This invention relates to machines for making pulp board, and embodies the use of a mold roll on which the pulp or fibrous material is collected and dried by exhausting air from the roll, a couch roll to which the sheet of pulp is delivered from the mold roll, and a forming roll to which the sheet is delivered from the couch roll, and on which the sheet is wound and compressed, and finally cut and delivered.

The object of the invention is to provide an improved construction with respect to the various parts of such a machine, the improvements relating especially to the means for feeding the stuff to the mold roll, means for delivering the same to the respective rolls, and the means for cutting the completed sheets, the latter including a reciprocating cutter which is automatically operated, avoiding the hand operations heretofore employed.

A further object of the invention is to provide improved means for supporting the rolls and imparting pressure thereto.

The automatic operating devices for the cutter include an electric motor and a switch controlling the operation of said motor, the action of the switch being controlled by adjustable devices which permit a board of any desired thickness to be produced, the cutting action being effected when the board reaches the required thickness.

Improvements are claimed with respect to various other details of the machine, as more fully pointed out hereinafter.

In the accompanying drawings—Figure 1 is a plan of the machine. Fig. 2 is a central vertical cross section. Fig. 3 is a vertical cross section on the line 3—3 of Fig. 1. Fig. 4 is a vertical longitudinal section on the line 4—4 of Fig. 1. Fig. 5 is a similar section on the line 5—5 of Fig. 1. Figs. 6 and 7 are enlarged details of the cutter. Figs. 8, 9 and 10 are enlarged views in detail of the switch which controls the motor which operates the cutter.

Referring specifically to the drawings, 6

indicates the mold roll, 7 the couch roll and 8 the forming roll. The mold roll is made of two circular metal ends 6^a, with tubular trunnions 6^b and inclined inner flanges 6^c which space and support radial partitions 6^d which connect the two ends. Around the outside edges or face of the partitions and extending from end to end of the roll is a perforated metal cover 6^e, of any construction which will allow water to pass through but will retain the pulp fiber. Bearings for the trunnions 6^b are formed in the exhaust air chambers 9. In the air chamber on each side of the machine is a cross bar 9^a which supports a pipe 10 which extends through the center of the roll and is stationary. This pipe carries a metal pan 11 one side of which projects almost to contact with the inner part of the rim structure of the roll. The pan is of suitable shape to catch the water passing through the perforated cover, and that part of the pipe 10 extending through the pan is slotted as at 10^a to drain the pan as it catches the water. The pipe also supports a valve 12, by means of arms 12^a, and this valve extends from end to end of the roll and bears against the inner edges of the partitions, as they rotate, and is wide enough to cut out two of the compartments between the partitions from the effect of the air suction, as shown in Fig. 2.

The air chambers at the ends of the roll are made in two parts, the lower part 9^b being stationary and fixed to the base of the machine, and the upper part, 9, has an external flange 9^c which works in an annular hydraulic chamber 9^d to which pressure may be supplied from any suitable source. The hydraulic pressure thus supports the roll, and by means of said pressure the mold roll is held up against the couch roll with a constant pressure, regardless of the thickness of the pulp passing between said rolls, thus avoiding the danger of damage to the perforated cover with an unusually thick sheet of pulp, which damage is often realized with the customary spring used for this purpose, the hydraulic pressure being constant under all conditions. Mounted above the mold roll is a stock box 13, supported by arms 13^a extending from the top of the air chambers 9. The metal ends of this stock box fit in grooves 6^f in the periphery of the ends of the mold roll, thus preventing stuff and water flowing over the 110

ends of the mold roll before the water is drawn through the perforated cover. The arm carrying the stock box is so arranged that the box may be moved toward or from the couch roll as desired, the box being supported by blocks 13^b fitting in circumferential ways 13^c in the ends of the arms and permitting said box to be shifted. The box has a slide valve or gate 13^d controlling the flow of stuff therefrom. The direction of rotation of the mold roll is toward the edge of the bottom of the stock box.

The air chambers at the ends of the mold roll communicate with exhaust mains 14, and each of these mains communicates with an air chamber 15 of the couch roll, a damper 14^a being provided to control the suction from the mold roll and a valve 15^a controlling the suction from the couch roll, and by means of these dampers the effect of suction in the mold and couch rolls may be regulated. The main air pipe 14, at each side, will be connected to any suitable air exhauster (not shown).

25 The exhaust causes a partial vacuum inside of the mold and couch rolls. The gate in the stock box (which will be fed by a stock pipe not shown) is raised, and the stuff runs out onto the face of the mold roll against the direction of rotation of the roll. By force of gravity and the partial vacuum within the roll the water is drawn through the cover and into the pan and passes away through the pipe 10. This is believed to be an improvement over machines using a vat in which the mold roll operates, for with the exception of the two compartments which are shut off by the valve, the sheet of pulp is under direct action of the air passing through the sheet for the entire circumference of the roll, instead of only a fraction of that circumference, as with the vat machines, so that with the same speed a drier sheet will be formed, or for the same degree of dryness the machine may be run at a higher speed. This is an important advantage resulting from feeding the pulp from the box instead of collecting the same in a vat.

50 The valve 12 shuts off the corresponding compartments just before they reach the point of contact with the couch roll 7, so that the suction within the couch roll may take the sheet from the mold roll. The respective rolls are driven by meshing spur gears 7^a and 6^c at one end thereof.

The construction of the couch roll is similar to that of the mold roll with respect to its end plates 7^b hollow trunnions 7^c, partitions 7^d and perforated cover 7^e, but its bearings formed by the air chambers 15 are stationary, and by means of cross bars 15^b these air chambers support a stationary shaft 7^e which passes through the center of the roll, and this shaft carries a valve 16,

supported by arms 16^a. There is no pan and pipe in this roll, as there is no water to carry off aside from what the air picks out of the sheet and conveys in the form of spray. The valve 16 shuts off the air in 70 a plurality of compartments, acting just before they successively reach the point of contact with the forming roll, so that the forming roll may pick the sheet from the couch roll, and the valve is of such width 75 that the suction does not again act in its compartments until the face is again sealed with the pulp on the mold roll. On the side of the couch roll bearing at one side of the machine is a bracket 17 carrying a shaft 17^a with a pinion 17^b meshing with the gear 7^a and a driving pulley 17^c to rotate it. The couch and mold rolls are rotated by the gears, but the forming roll 8 is driven by contact with the couch roll. 85

The sheet of pulp is wound or rolled up one layer on top of another until the desired thickness is formed, when it is cut across and removed. In some machines it is necessary to stop the machine, in order 90 to cut the sheet and remove the same in the most convenient way by hand. The forming roll of the present machine has an automatic cutter, whereby the sheet is automatically gaged for thickness, and then cut, when 95 its forward end drops onto the small rolls 18 by which it is guided to the canvas belt 19 which carries it on for subsequent operation.

The forming roll is constructed of circular spiders 8^a mounted on a shaft 8^b and having a sheet metal cover 8^c securely fastened to the rims of the spiders, the shaft being mounted in bearings on the pillars 20 on the frame of the machine. At one point of the circumference of the roll is a longitudinal groove or recess formed by a box or track 8^d, to receive the knife and carriage, which track extends from end to end of the roll and beyond the plates at each end. This track is undercut to receive the knife carriage, shown particularly in Figs. 6 and 7, the metal face of the roll being slotted to allow the knife 21 to project up through the same. The knife is a triangular piece of sheet metal, sharpened on both sides and fastened at the bottom to metal strips 21^a, forming the carriage, and the carriage is provided with small rolls 21^b at each end to cause it to slide easily along the track. In the bottom of the carriage is a groove through which runs a sprocket chain 22, which extends along the track and around the sprockets 22^a supported at the end thereof. Two tightener sprockets 22^b are 110 provided, inside the roll, on opposite sides of a driving sprocket 22^c, the sprockets 22^b being carried by the outer arms of bell cranks 22^d the lower ends of which may be moved apart, to tighten the chain, by means 115 120 125 130 135

of a right and left screw rod 22^e provided with a hand wheel at the end of the roll. The connection between the bell cranks and the screw rod is formed by collars 22^f, nuts 22^g and springs 22^h coiled around the rod between the collars and the nuts, the bell cranks being attached to the collars, and the coiled springs acting as shock absorbers when the knife is started or stopped. The 10 knife carriage has dogs 22ⁱ held down by springs 22^j, and these dogs engage in the chain to drive the knife carriage either way. At the ends of the knife track are spring 15 bumpers 8^e, and when the knife carriage reaches either end of the track it will strike one of these bumpers and stop, the chain dropping through the bottom of the track and around the sprocket, and at this time the rear dog will drag on the moving chain 20 and prevent the knife carriage from bouncing back after striking the bumper. When the chain is run in the opposite direction the knife carriage will be picked up and caused to travel back across the face of the roll.

25 The chain is operated by an electric motor 23 mounted within the forming roll on the opposite side of the shaft from the knife, thereby serving to balance the roll. The motor shaft 23^a is geared to a shaft 23^b 30 geared to another shaft 23^c which is geared to the shaft 23^d which carries the driving sprocket 22^e, the shafts being provided with suitable supports in the roll and with bevel gears adapted to the purpose.

35 When one sheet is ready to be cut the motor is run in one direction and the knife is thereby driven along the track and across the face of the roll in a corresponding direction. When the next sheet is ready to be 40 cut the current in the motor is reversed and it is driven in the opposite direction, and the knife then travels back across the roll. This action is automatic and is governed by the thickness of the sheet, and is accomplished by a switch controlling the motor 45 circuit.

The bearing boxes 24 for the shaft of the 50 forming roll slide in T slot ways 24^a at the top of the frames 20, in a direction toward or from the couch roll. The forming roll is held with a constant pressure against the couch roll by means of hydraulic cylinders 55 the piston rods 25^a of which are connected to the bearing boxes 24, the cylinders being fastened to the frame, the pressure being introduced into the cylinders from any suitable source on the side of the pistons opposite to the couch roll, and when the tail end of a thick sheet of pulp has passed 60 through the pinch between the forming and couch rolls the hydraulic pressure returns the forming roll slowly toward the couch roll, thus avoiding any damage to either roll.

The bearing at one end of the forming

roll is equipped with an electric switch shown particularly in Figs. 8, 9 and 10. A collar 26 is fastened to the shaft, and this collar carries a finger 26^a projecting radially therefrom and pivotally connected thereto at 26^b, and held out at right angles to the axis of rotation by a spring 26^c. Fastened to the outer end of the support for the bearing is a small bracket 27 having a bearing 27^a with a bushing 28 therein, and the inner end of the bearing is flanged as indicated at 28^a and has four electric connections or contacts 28^b arranged on quarters around the same two connections being for the generator wires and two for the motor wires, the 70 motor wires being connected to a pair of segmental contact pieces 28^c fastened to the base, with which a pair of fingers 28^d carried by the shaft come in contact at each revolution of the roll, the fingers being connected to the motor by wires 28^m, whereby the motor circuit is closed as the shaft is rotated and while the contact pieces and fingers are in contact. Inside of the bearing 27^a and rotating on the bushing 28 is a ratchet wheel 29 having four electric contact points 29^a connected together in pairs corresponding to the four contacts 28^b and arranged to close the contact therewith. The finger 26^a is engageable with this ratchet wheel. Inside of the bushing 28 is a longitudinally movable bar 30 which is non-rotatable and is movable lengthwise for adjustment. The inner end of this bar has a cam 30^a attached thereto, and arranged to strike and turn the finger 26^a on its pivot as it comes around into position to engage with the ratchet. This bar 30 is marked off into 100 inches and can be adjusted to vary the distance of its cam from the ratchet wheel. At one point on the finger 26^a is a notch 26^m through which the cam may pass when the notch registers with the cam. At other 105 times the finger strikes the cam and is swung outwardly thereby so that it will not engage the ratchet wheel.

When the bar 30 is adjusted so that its cam 30^a is placed in position for any desired thickness of board, the pulp between the couch roll and the forming roll gradually 110 forces the bearing of the forming roll nearer to the ratchet, and at each revolution the cam strikes the finger and throws it out so that it will not engage the ratchet, until the bearing carrying the collar and the 115 finger has moved out far enough for the notch on the finger to register with the cam, at which time the cam passes through the notch, and the finger, being no longer 120 swung out engages with the ratchet and turns it one eighth revolution, the ratchet having eight teeth spaced apart corresponding to one half the distance between the contacts. This closes two of the contacts 125 and starts the motor which drives the knife 130

and cuts the sheet which then drops off onto the delivery rolls and apron 19. At the same point of the next revolution the pulp board is still in the pinch between 5 the couch and forming rolls, and the action being the same the finger engages the ratchet again and turns the same one eighth revolution thereby opening the circuit and stopping the motor, and the board then 10 passing from between the rolls the hydraulic pressure returns the forming roll to contact with the couch roll for the next operation. The next time a board of the same thickness is in the pinch, the ratchet 15 is again turned one eighth revolution, bringing the electric contacts together again, but this time in opposite relationship with respect to the positive and negative terminals, causing the current to flow to the 20 motor in the opposite direction and consequently rotating it in the opposite direction, and driving the knife in opposite direction along the track to cut off the next sheet.

It will be seen that by means described 25 the thickness of the sheet may be measured and controlled, and the knife actuated to cut off the sheet automatically as soon as the desired thickness is reached, and the sheets may be cut and removed without 30 stopping the machine.

The invention is not limited to the exact embodiment shown, but various modifications may be made within the scope thereof, and no limitation in this respect is implied.

Having thus described my invention, what I claim as new and desire to secure by Letters Patent is:

1. In a machine for making pulp board, 40 the combination of a perforated molding roll, means to flow pulp thereon at the upper part thereof to form a sheet thereon, means to produce suction through the perforations in said roll, a couch roll co-operating with said molding roll to release the sheet therefrom at a certain point on the upper part of its surface, and a valve in the molding roll arranged to prevent suction through the perforations in the part of 45 the roll at said point, the perforations in the roll being otherwise open for the suction of air therethrough about the whole circumference of the roll.

2. A molding roll for a machine of the 55 kind stated, having a perforated cover, a hollow trunnion and an exhaust conduit communicating therewith, a water pan located in the roll and provided with a pipe leading therefrom and through the trunnion, and a valve supported on the pipe and controlling a portion of the perforations in the cover.

3. The combination with a molding roll, 60 of a stock box located beside the roll and arranged to feed stuff onto the surface of

the roll in a direction contrary to its direction of rotation.

4. The combination with a molding roll and a couch roll, of a stock box located beside the roll and arranged to feed stuff onto 70 the surface of the roll in a direction contrary to its direction of rotation, the stock box being adjustable with respect to the couch roll.

5. In a machine for making pulp board, 75 the combination with molding and couch rolls, of suction air chambers supporting the journals of the molding roll, and communicating with the interior of said roll, and fluid pressure supports for said air 80 chambers.

6. In a machine for making pulp board, 85 the combination with molding and couch rolls, of tubular suction air chambers communicating with the interior of said molding roll and supporting the journals thereof, the air chambers having two parts movable with respect to each other, and fluid pressure supporting devices between said two parts.

7. In a machine for making pulp board, 90 the combination of a forming roll, a cutter carried thereby, and a motor carried by the roll and operatively connected to the cutter to sever a sheet on the roll.

8. In a machine for making pulp board, 95 the combination of a forming roll, a cutter carried thereby, and a motor carried by the roll and operatively connected to the cutter, to sever a sheet on the roll during the rotation thereof.

9. In a machine for making pulp board, 100 the combination of a forming roll, a cutter carried thereby and a motor carried by the roll and automatically actuated by the rotation of the roll to operate the cutter.

10. In a machine for making pulp board, 105 the combination of a forming roll, a cutter and its motor carried thereby, and means controlled by the thickness of the sheet on the roll to actuate the motor and operate the cutter to sever the sheet.

11. In a machine for making pulp board, 110 the combination of a forming roll, a cutter arranged to sever a sheet thereon, an electric motor operatively connected to the cutter, and a switch operating automatically with the roll and controlling the motor circuit.

12. In a machine for making pulp board, 115 the combination of a forming roll, a cutter carried thereby and adapted to sever a sheet thereon, an electric motor carried by the roll and operatively connected to the cutter and a switch operated by rotation of the roll and controlling the motor circuit.

13. In a machine for making pulp board, 120 the combination of a forming roll, a cutter arranged to sever a sheet thereon, an electric motor operatively connected to the cutter, and a switch operating automatically with 125

the roll and governed by the thickness of a sheet on the roll, to control the motor circuit.

14. In a machine for making pulp board, 5 the combination of a forming roll having a track across its periphery, a knife carriage movable back and forth on said track, the knife being adapted to cut a sheet on the roll when moved in either direction, and 10 means to drive the carriage.

15. In a machine for making pulp board, the combination of a forming roll having a longitudinal slot in its periphery, a track behind said slot, and a cutter carriage mov- 15 able back and forth along the track, the cutter projecting through the slot to sever a sheet on the roll, when moved in either direction.

16. In a machine for making pulp board, 20 the combination of a forming roll having a longitudinal slot in its periphery, a track behind said slot, and a cutter carriage movable back and forth along the track, the cutter projecting through the slot to sever 25 a sheet on the roll, a belt carried by the roll and connected to the carriage to drive the same, and means to drive the belt.

17. In a machine for making pulp board, the combination of a forming roll having a 30 longitudinal slot in its periphery, a track behind said slot, and a cutter carriage movable back and forth along the track, the cutter projecting through the slot to sever a sheet on the roll, a belt carried by the 35 roll and connected to the carriage to drive the same, and means to drive the belt including a motor carried by the roll and geared to the belt.

18. In a machine for making pulp board, 40 the combination of a forming roll having a longitudinal slot in its periphery, a track located behind said slot and extending beyond the ends of the roll, and a cutter carriage movable on the track from one end to 45 the other thereof, and having a cutter projecting through the slot and adapted to sever a sheet on the roll.

19. In a machine for making pulp board, the combination of a forming roll having a 50 longitudinal slot in its periphery, a knife movable in said slot, to sever a sheet on the roll, a driven belt carried by the roll and operatively connected to the knife to move the same, and a belt tightener carried by 55 the roll and engaging the belt.

20. In a machine for making pulp board,

the combination of a forming roll having a longitudinal slot in its periphery, a knife movable in said slot, to sever a sheet on the roll, a driven belt carried by the roll and 60 operatively connected to the knife to move the same, and a spring pressed belt tightener carried by the roll and engaging the belt.

21. In a machine for making pulp board, the combination of a forming roll having a 65 slot across the same, a belt carried by the roll, a knife movable in said slot, a dog connected to the knife and engageable with the belt, and means to drive the belt in either direction.

22. In a machine for making pulp board, the combination of a couch roll, a forming roll, pressure devices tending to force the forming roll toward the couch roll, a cutter for severing the sheet on the forming roll, 75 and means governed by the thickness of the sheet between said rolls and actuated by the movement of the forming roll from the couch roll to operate the cutter.

23. In a machine for making pulp board, 80 the combination of couch and forming rolls between which the sheet is pinched, pressure devices tending to force the rolls together and permitting the rolls to separate as the sheet therebetween increases in thickness, a cutter adapted to sever a sheet on the forming roll, and electric devices to operate the cutter, including a switch automatically actuated by the rotation of one of 85 said rolls when the sheet reaches the desired 90 thickness.

24. In a machine for making pulp board, the combination of couch and forming rolls between which the sheet is pinched, pressure devices tending to force the rolls together and permitting the rolls to separate 95 as the sheet therebetween increases in thickness, a cutter adapted to sever a sheet on the forming roll, and electric devices to operate the cutter, including a switch automatically 100 actuated by the rotation of one of said rolls when the sheet reaches the desired thickness, one of the switch members being adjustable to produce its operation at a desired thickness of the sheet.

In testimony whereof I affix my signature in presence of two witnesses.

HERBERT A. MOODY.
